UNITED STATES PATENT OFFICE.

CARLISLE A. LINCOLN, OF BUFFALO, NEW YORK, ASSIGNOR TO THE HOUDAILLE COMPANY, OF BUFFALO, NEW YORK, A CORPORATION OF DELAWARE.

CLOSURE MEMBER FOR SPRING COVERS.

Application filed November 27, 1923. Serial No. 677,212.

To all whom it may concern:

Be it known that I, CARLISLE A. LINCOLN, a citizen of the United States, residing at Buffalo, in the county of Erie and State of New York, have invented certain new and useful Improvements in Closure Members for Spring Covers; and I do hereby declare the following to be a full, clear, and exact description of the invention, such as will enable others skilled in the art to which it appertains to make and use the same.

The present invention relates to spring covers or boots and more particularly to certain improvements in connection therewith tending to improve the appearance and efficiency of the cover.

Certain copending applications filed of even date herewith have disclosed a spring cover comprising either sectional casings or a casing extending continuously from the central portion to the ends of the spring, together with closure members for improving the appearance and substantially sealing the casing adjacent the spring clips.

It is the object of the present invention to provide a simple and improved form of closure member which tightly seals the spring cover at the region adjacent the spring clip. With this end in view, a feature of the invention contemplates the provision of a closing member extending about the spring adjacent the spring clip and interposed between the spring clip and the body of the spring, the closure member being so constructed that when assembled in position it may not be removed without removal of the clip.

In the accompanying drawings illustrating the preferred form of the invention, Fig. 1 represents a top plan view of a portion of a spring cover adjacent a spring clip with the improved closure member applied thereto; Fig. 2 is a side elevation partly in section of the improved closure member; Fig. 3 is a detail illustrating that portion of the closure member which extends about the bottom and sides of the spring; and Fig. 4 is a detail illustrating the top portion of the closure member.

The spring casing may be of the usual type indicated generally at 10 and having an opening to allow the upper ends of the spring clip 12 and the clip bolt 14 to project therethrough. The clip bolt is intended to bind the opposite legs of the yoke 12

against the sides of the spring and is held in position through a head 16 formed upon the bolt and a nut 18 engaging with the opposite threaded end of the bolt. In addition, the clip may be held in position through a rivet or stud 20 passing through the bottom portion of the clip and entering the lower leaf of the spring. According to the present invention, the spring clip is removed from the spring together with the bolt 14 and a closure member 22 of resilient material positioned to extend about the bottom and sides of the spring, as indicated. This closure member is provided with a flat depression 24 extending lengthwise which is adapted to receive and fit the yoke 12. After the closure plate has been assembled with the yoke of the spring clip, the pressure of the yoke causes a series of inclined flanges 26 and 27 projecting from opposite sides of the closure plate to yieldingly engage with the flexible cover or casing adjacent thereto, as clearly indicated in Fig. 2. The top portion of the casing adjacent the clip bolt is engaged by a corrugated closure plate 30 having a central depression 32 adapted to engage beneath the spring bolt and cause a downward pressure to be exerted at the outer edges of the laterally extending flanges 34 in a manner to cause these flanges to engage and bear firmly upon the casing at the top of the spring. The insertion of the spring bolt into the clip obviously locks the closure plate in position and prevents its removal either accidentally or otherwise. This form of closure presents a neat, well fitting appearance and accomplishes the necessary holding and sealing functions of the cover adjacent the spring clips. It should be understood in addition that although the illustrated embodiment of the invention shows closure members which extend completely about the spring, necessitating the removal of the entire spring clip, nevertheless it may be desirable to employ merely a top closure member which necessitates only the removal of the clip bolt without disturbing the main portion of the spring clip.

While it is preferred to employ the specific construction and arrangement of parts shown and described, it will be understood that this construction and arrangement is not essential except so far as specified in the claim and may be changed or modified with-

out departing from the broader features of the invention.

The invention having been described, what is claimed is:

- 5 A closure member for spring covers comprising a resilient plate extending about the bottom and sides of the spring beneath the spring clip, a second plate extending across the top of the spring beneath the tie bolt,

each of the plates having a groove or depression to cause it to be locked to the spring clip, and oppositely directed flanges which bear upon the adjacent portions of the spring cover when the closure is locked in place between the clip and the body of the spring.

CARLISLE A. LINCOLN.
